FIREPLACE

Lyman R. Andrew, Santa Rosa, Calif., assignor to Viking
Universal Corporation, Cotati, Calif.

Filed July 5, 1973, Ser. No. 376,548

Term of patent 14 years

Int. Cl. D23—03

U.S. Cl. D23—97

FIG. 1

FIG. 2

FIG. 3

FIG. 4

FIG. 5

FIG. 1 is a perspective view of a fireplace showing my new design.

FIG. 2 is a front elevational view thereof.

FIG. 3 is a top plan thereof.

FIG. 4 is a rear elevational view thereof.

FIG. 5 is a side view thereof.

The dashed lines in FIGS. 1 and 2 indicate a conventional fireplace screen.

I claim:

The ornamental design for a fireplace, as shown and described.
